DISPLAY RACK FOR FLOOR CLEANING EQUIPMENT AND THE LIKE

Murray Federman, Brooklyn, N.Y., assignor to Glamorene, Inc., Clifton, N.J., a corporation of New York

Filed Apr. 16, 1965, Ser. No. 34,836

Term of patent 14 years

(Cl. D80—10)

FIGURES 3 and 4 are respectively opposite side elevational views thereof;

I claim:

The ornamental design for a display rack for floor cleaning equipment and the like, as shown.
